UNITED STATES PATENT OFFICE.

LEONARD D. DAVIS, OF ERIE, PENNSYLVANIA.

STEAM-ENGINE CROSS-HEAD.

SPECIFICATION forming part of Letters Patent No. 394,345, dated December 11, 1888.

Application filed November 29, 1887. Serial No. 256,480. (No model.)

To all whom it may concern:

Be it known that I, LEONARD D. DAVIS, a citizen of the United States, residing at Erie, in the county of Erie and State of Pennsylvania, have invented certain new and useful Improvements in Steam-Engine Cross-Heads; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention consists in the improvements in steam-engine cross-heads hereinafter set forth and explained, and illustrated in the accompanying drawings, in which—

Figure 1 shows my improved cross-head partly in elevation and partly in section. Fig. 2 is a perspective view of one of the adjustable shoes used on my improved cross-head.

Like letters refer to like parts in both the figures.

In the construction of steam-engines with stationary guides and adjustable cross-heads heretofore the shoes have been made to adjust separately by means of set-screws and other like devices, and great difficulty has been experienced in adjusting the shoes separately without getting the cross-head out of line with the cylinder and crank-pin. To overcome this difficulty, I make my shoes so that they are both adjusted at the same time and so that the adjustment of both shoes is alike, so that the adjustment of the cross-head cannot interfere with the lining up of the operative parts of the engine.

40 In the construction of my improved cross-head shown, A A are sections of the guides in which the cross-head operates, B the piston-rod, and C the connecting-rod, these parts being of the ordinary construction.

45 The central portion of the cross-head M is chambered out in the usual manner to receive the box D on the end of the connecting-rod C, and has an ordinary cross-head pin, E, therein. On the end of the cross-head which

is secured to the piston-rod I make a projection or sleeve, F, into which the end G of the piston-rod B is secured. On the outside of the sleeve F, I cut a screw-thread, f, upon which the nut H fits.

The nut H is provided with a groove, I, 55 adapted to receive the ends of arms J J on the ends of the shoes L L. The shoes L L are fitted one on each side of the cross-head M by means of diagonal joints N, so that when they are moved upward, by means of 60 the grooved nut H operating on the arms J J, they are also moved outward against the slides A A, so as to take up any wear, and, vice versa, the reverse movement of the nut H moves the shoes L L back from the guides 65 A A. In one of the sides of the shoes L L, I preferably cut slots O, through which I insert set-screws P, which are tapped into the shell of the cross-head M, so that when the proper adjustment has been made by means of the 70 nut H the set-screws P may be tightened up, so as to relieve the nut H of the strain caused by the friction of the shoes L L against the guides A A. I can, however, make my improved cross-head without the set-screws P, if 75 desired.

Having thus described my invention, so as to enable others to construct and operate the same, what I claim as new, and desire to secure by Letters Patent of the United States, 80 is—

1. The combination, in a cross-head of a steam-engine, of adjustable shoes on each side thereof, with a grooved nut adapted to move both shoes longitudinally at the same 85 time, substantially as and for the purpose set forth.

2. The combination, in a cross-head of a steam-engine, of the body M, having the screw-threaded sleeve F at one end thereof, 90 and the grooved nut H, operating on said sleeve, with the shoes L L, having arms J J, operating in the groove in said nut, whereby said shoes may be simultaneously moved longitudinally, substantially as and for the purpose set forth.

3. The combination, in a steam-engine cross-head, of the diagonal slides N on the body of

the cross-head and the shoes L L, having inclined faces N', operating longitudinally on the slides N, and set-screws P, for securing the shoes L L when adjusted, with the arms 5 J J on said shoes and the grooved nut H, engaging with said arms for adjusting the shoes longitudinally, substantially as and for the purpose set forth.

In testimony whereof I affix my signature in presence of two witnesses.

LEONARD D. DAVIS.
